UNITED STATES PATENT OFFICE.

JULIUS SCHMID, OF MONTGOMERY, NEW YORK.

COMPACT CARRIER.

Application filed December 13, 1922. Serial No. 606,627.

To all whom it may concern:

Be it known that I, JULIUS SCHMID, a citizen of the United States, residing at Montgomery, in the county of Orange and State 5 of New York, have invented new and useful Improvements in Compact Carriers, of which the following is a full, clear, and exact specification.

My invention relates to powder compact 10 containers and refers particularly to powder compact containers which act as powder compact carriers for the replacement of such compacts within a compact box.

Powder compacts, that is face and similar 15 powders in compact form, have largely replaced the loose powders because of their increased cleanliness, ease of carrying and more efficient application.

Compacts of this character are usually 20 carried in so-called compact boxes, and the compacts, because of their consumption through use, usually become exhausted long before the compact box is useless, and, as these boxes are generally artistic and somewhat expensive, it is desirable that the owner 25 be afforded a means whereby the exhausted compact may be removed and a new compact easily inserted within the compact box.

I have invented such a compact carrier 30 which, in addition to its ease of removal from and insertion within a compact box, possesses many valuable advantages not found in other devices adapted to this purpose.

Powder compacts are extremely friable 35 and subject to injury, and hence, must be carefully protected. In view of the powder's application to the skin, it should be carefully protected from accumulated dirt and dust. As these compacts are usually 40 employed in compact boxes having a mirror therein, it is desirable that the mirror face should be protected from the powder. As a new powder puff is usually used with a 45 new compact, it is desirable that they should accompany each other in equal hygienic condition.

The compact carrier of my invention possesses all of these desirable and valuable 50 qualities and presents a means whereby a powder compact and a powder puff, suitable for replacement purposes, are preserved in hygienic unbreakable condition, before use and during use can be readily inserted with- 55 in a powder box and maintained therein free from accidental displacement.

In the accompanying drawings, illustrating one form of the device of my invention, similar parts are designated by similar numerals.

Figure 1 is a perspective view of a compact box containing one form of my device in closed position.

Figure 2 is a top view of Figure 1 in open position, partly broken away.

Figure 3 is a perspective view of the compact container of Figure 2 with the cover on.

Figure 4 is a perspective view of the compact container of Figure 2 with cover, compact and puff removed.

Figure 5 is an enlarged cross-section through the line 5—5 of Figure 1.

The particular form of compact carrier of my invention suitable for the re-loading of compact boxes shown in the accompanying drawings, comprises an annular bottom 10 having the upwardly extended annular flange 11. The flange 11 has an inset recess 12 and a plurality of outwardly exposed binding members 13, 13, 13, formed in this case by the outward forcing of a portion of the flange 11 itself. The flange 11 has also a plurality of slot openings 14, 14, 14, within which a finger nail or other device may be inserted for ease of removal of the compact 15 container from within a compact box. The lid or cover, of the compact carrier comprises the annular member 15 having the slightly impressed annular flange 16, thus forming an extended portion, or head, 17 around the edge of the member 15. The cover is of such size and shape that the flange 16 will fit within the flange 11 of the bottom with sufficient friction and tightness to prevent accidental dislodgment of the 20 cover but allow of its desired removal by an upward movement of the head 17. The compact carrier is of such height that the head 17 will be slightly above the bottom flange of a compact box, in order to allow of the 25 removal of the cover without the removal of the compact carrier from the compact box. The compact carrier is of such diameter and of such proportions that it will fit simply 30 within a compact box, the recess 12 allowing of the insertion of the hinge of the compact box therein and the binding members 13, 13, 13 abutting upon the inner face of the flange of the compact box.

Figures 3 and 4 show the compact carrier, 110 while Figures 2 and 5 show the compact carrier in placement within a compact box.

The compact box comprises a bottom member formed of the disc-like member 18 and the upwardly extended flange 19, to the latter of which is hinged at 20 the flange 21 of the cover member 22. The compact carrier is maintained in position within the compact box by the frictional engagement of the binding members 18, 13, 13 with the inner face of the flange 19 and, when the compact box cover is in raised position, the cover of the compact carrier can be readily and easily removed by an upward movement upon the bead 17, thus exposing the contents for use. A compact 23 is fixedly attached within the compact carrier and a powder puff 24 is placed thereon. The cover of the compact box carries a mirror 25.

It will be seen from the above that my compact carrier, when employed with its cover, is of such form and construction that it is adapted for receiving and carrying a powder compact and a powder puff and maintaining them clean from contact with dirt and dust; that it protects the compact from accidental damage; that it can be readily inserted within a powder box and retained therein; that its cover protects the contents from dust and the mirror from the powder; and that the cover can be readily removed to obtain access to the compact and the puff.

It is also evident that my compact carrier may be employed without its cover, simply as a means for the ready replacement of compacts within a compact box.

I do not limit myself to the particular size, shape, number and arrangement of parts as shown and described, as these are given simply as a means of clearly describing my invention.

What I claim is:—

1. In a compact carrier, in combination, a bottom having an upwardly extended flange, a plurality of outwardly extended binding members carried by the flange, a recess within the flange capable of receiving the hinge of a hinged powder box into which the compact carrier is inserted and a plurality of openings within the bottom flange.

2. In a compact carrier, in combination, a bottom having an upwardly extended flange, a plurality of outwardly extended binding members carried by the flange and a recess within the flange capable of receiving the hinge of a hinged powder box into which the compact carrier is inserted.

3. In a compact carrier, in combination, a bottom having an upwardly extended flange,

a plurality of outwardly extended binding members carried by the flange, a recess within the flange capable of receiving the hinge of a hinged powder box into which the compact carrier is inserted and a removable cover for the bottom member.

4. In a compact carrier, in combination, a bottom having an upwardly extended flange, a plurality of outwardly extended binding members carried by the flange, a recess within the flange capable of receiving the hinge of a hinged powder box into which the compact carrier is inserted and a removable cover the flange of which will telescope within the bottom flange.

5. In a compact carrier, in combination, a bottom having an upwardly extended flange, a plurality of outwardly extended binding members carried by the flange, a recess within the flange capable of receiving the hinge of a hinged powder box into which the compact carrier is inserted, a removable cover the flange of which will telescope within the bottom flange and an extended bead around the cover.

6. In a compact carrier, in combination, a bottom having an upwardly extended flange, a plurality of outwardly extended binding members carried by the flange, a recess within the flange capable of receiving the hinge of a hinged powder box into which the compact carrier is inserted, a removable cover for the bottom member and an extended bead around the cover.

7. In a compact carrier, in combination, a bottom having an upwardly extended flange, a plurality of outwardly extended binding members carried by the flange, a recess within the flange capable of receiving the hinge of a hinged powder box into which the compact carrier is inserted, a removable cover for the bottom member and a plurality of openings within the bottom flange.

8. In a compact carrier, in combination, a bottom having an upwardly extended flange, a plurality of outwardly extended binding members carried by the flange, a recess within the flange capable of receiving the hinge of a hinged powder box into which the compact carrier is inserted, a removable cover the flange of which will telescope within the bottom flange, an extended bead around the cover and a plurality of openings within the bottom flange.

Signed at New York city, in the county of New York and State of New York this 12th day of December, 1922.

JULIUS SCHMID.
